ASSOCIATIVE MEMORY

Walter K. French, Montrose, N.Y., assignor to International Business Machines Corporation, New York, N.Y., a corporation of New York

Filed July 11, 1960, Ser. No. 42,005
5 Claims. (Cl. 235—61.11)

This invention relates to an associative memory system and more particularly to a system for reading out of an associative memory a word having an identification tag corresponding to the particular identification tag fed to the input to the memory.

In an associative memory each word is stored therein at an arbitrary or unknown location and has associated therewith an identification tag peculiar to it. When this word is desired, the memory is "addressed" at its input with a tag corresponding to the identification tag of said desired word. A comparison is indicated between the identification tag of the desired word and the tag at the input to the memory and read-out of the data digits associated with the word is achieved. In a fully associative memory, such as the one described herein, the tag may be in any position in the word, not necessarily consecutive digits. Furthermore, the position of this tag may be different on successive scans of the memory.

In accordance with the present invention, information is stored in the memory in the form of holes or no-holes in a record such as a punched card. The card is divided into rows and columns in the usual fashion. Each column designates a separate word. A tag portion of each column contains the tag digits and the data portion contains the data digits. The word is composed of tag digits and data digits. The card is operatively associated with X and Y coordinate electrodes corresponding respectively to the rows and columns of the card. A hole or a no-hole in a card will cause an electrical association between a related X and Y conductor intersection point. By feeding to the tag digit lines at the input to the memory an identification tag indicative of a desired word, only that word having the corresponding identification tag associated therewith will produce at the output of the system the data digits contained in the word.

In accordance with the present invention, the X and Y coordinate electrodes are composed respectively of strips of electroluminescent material and strips of photoconductive material. A hole at a coordinate point will couple the luminescence of a coordinate X strip to the coordinate Y photoconductive strip. This, in the usual fashion, reduces the impedance of the photoconductive strip, which reduction in impedance is an indication of the hole at said intersection point. The optical coupling between the X and Y strips as a function of the holes in a record card interposed therebetween determines the setting up of read-out circuitry for reading out the data digits associated with the identification tag.

The associative memory of this invention has a number of advantages. The word capacity may be quite high per unit volume. The access time is extremely low. Then, too, the memory system is easy to construct and maintain and is relatively inexpensive.

It is therefore one object of this invention to provide an associative memory which has a large word capacity per unit volume and in which the words may be stored at arbitrary or unknown locations in the memory.

It is another object of this invention to provide such a memory in which each word is composed of digits which at the beginning of each memory search may be divided arbitrarily into tag digits and data digits and in which a comparison of input tag digits to the memory is made with all of the word tag digits stored in the memory to select a single desired word wherein the data digits asso-

2

ciated with this desired word are read out. In subsequent scan some of these data digits may be used as tag digits and similarly some of the tag digits may be used as data digits. The comparison results in the setting up of read-out circuitry peculiar to the desired word while inhibiting the read-out circuitry associated with the undesired words.

Another object of the invention is to provide parallel inputs in the form of tag digits to the memory and to perform parallel comparisons with all of the word tags in the memory to select only one of said words and to achieve serial read-out of the data digits associated with the desired word.

Another object of the invention is to provide a system of the type mentioned above in which punched cards or tapes are used to store the words.

Another object of the invention is to provide a system in which punched cards or tapes are incorporated into a sandwich arrangement with X and Y coordinate electrodes which form discrete optical couplings between the X and Y intersecting points as determined by the punched holes in the cards or tapes and in which an input tag selects a particular word to achieve read-out of the data digits of this particular word.

These and other objects of the invention will become apparent from a detailed description of the accompanying drawings.

In the drawings:

FIGURE 1a is a perspective view of one embodiment of the invention showing the three members of the memory in spaced relation for a clearer illustration of the construction of the members;

FIGURE 1b is a fragmentary cross section of the Y photoconductive strips showing the manner in which electrical leads are attached thereto;

FIGURE 1c is a diagrammatic illustration of the means of supplying an A.C. signal to the electroluminescent X strips;

FIGURE 2 is a schematic diagram showing the functioning of the read-out circuitry constructed in accordance with this invention;

FIGURE 3 is a schematic diagram coupled with a chart to better illustrate the operation of the invention;

FIGURE 4 is a timing chart showing the relationship of various parts of the cyclic operation of the present invention.

Referring first to FIGURE 1a, the record card 10 may be an opaque punched card or tape having discretely defined digit areas thereon. These areas have X and Y coordinates corresponding to the intersecting points of the X and Y electrodes. The Y electrodes in this particular embodiment are composed of photoconductive strips and are carried by the plate 11. The X electrodes are composed of strips of electroluminescent material and are carried by the plate 12. The passage of current through the X strips causes them to luminesce. If the luminescence can read a Y strip, said Y strip will present a reduced impedance to current flow therethrough. As shown particularly in FIGURE 1b, the base 13 supports a Y strip 14. To the back of the strip is connected a contact conductor 15 extending the full length of the strip. At the end of the conductor 15 is connected the lead 16 to which is connected a voltage source (not shown). On the opposite side of the strip 14 is connected a second contact conductor 17 also extending the full length of the strip. This conductor 17 may be transparent or quite narrow longitudinally so as not to mask the entire surface of the Y strip. A lead 18 connects at the bottom of the conductor 17. In the absence of a light from an X strip, the strip 14 connecting conductor 17 to conductor 15 provides a high impedance to current flow therethrough. However, if light should radiate the strip 14 at any local

ized point thereon, said localized point will provide a low impedance path between leads **16** and **18**.

As seen in FIGURE 1a, positive voltage sources C_4 , C_5 , and C_6 are connected to leads **16** associated with each of the Y strips. The card **10** is shown as having five horizontal digit areas, each defined by two X strips. The top strip of each pair is the 0 area and the bottom is the 1 area. For instance, the hole at X_1Y_2 indicates a 0 and the hole at X_2Y_3 indicates a 1. A complete word is contained in each column. For illustration purposes only, let it be considered that the top six X strips contain the tag digits and the bottom four the data digits of the word. The identification tag for the Y_1 word is 111, for Y_2 word is 011, etc. If we now consider the effect of applying an A.C. signal to the X_1 tag line which is connected to the X_1 strip, we see that the potential at lead **18** of Y_1 is open (no hole at X_1Y_1) plus at lead **18** of Y_2 (hole at X_1Y_2) and open at lead **18** of Y_3 (no hole at X_1Y_3). By a plus is meant a voltage approximately equal to the positive voltage supply of the C_4 , C_5 , or C_6 . By an "open" is meant an open circuit between leads **16** and **18** of the Y strip. An open circuit between these leads means that the actual voltage of the Y strip lead **18** would be that of its associated P point (FIGURE 2). The A.C. generator **50** of FIGURE 1c supplies the necessary signals to the X strips.

Let it now be assumed that the desired word for read-out has a tag of 011 from most to least significant digit. The A.C. address generator introduces an argument tag in the form of A.C. signals on the complement tag digit lines (100). Therefore, A.C. signals are applied to X_2 , X_3 , and X_5 strips. Due to the hole at X_2Y_1 , the Y_1 strip presents a low impedance and its associated lead **18** has a plus voltage thereon from supply C_4 . Due to the hole at X_2Y_3 or the hole at X_5Y_3 , strip Y_3 presents a low impedance and its associated lead **18** also has a plus voltage thereon from C_4 . Only on Y_2 strip lead **18** is there an open circuit. Thus, the Y_2 word is selected by the complement address applied to the tag digit lines. To observe the results of this, reference is now made to FIGURE 2.

The latches **19**, **20**, and **21** are normally reset, having their reset outputs down to a relatively low potential with respect to the potential on lines C_4 , C_5 , and C_6 . Latches of the type shown in the patents to Loque, 2,825,821, and Henie, 2,861,199, may be employed. These outputs connect through control lines C_1 , C_2 , and C_3 through appropriate resistors to the cathodes of diodes D_1 through D_{18} . Consequently, points P_1 through P_9 are normally at a potential to forward bias all of the diodes. The voltage to the plate of all the diodes is supplied from the positive supply connected to the input resistors to the gates associated with the sense lines S_1 through S_6 . After the addressing of the memory as described above, P_1 and P_3 through P_9 go positive to block diodes D_1 , D_2 , and D_5 through D_{18} . Since there is no change at P_2 , diodes D_3 and D_4 are still forward biased. Therefore, sense lines S_1 , S_3 , S_5 , and S_6 go positive. Only S_2 and S_4 remain negative. Now also referring to the timing chart of FIGURE 4, we see that a pulse at T_1 conditions gates **22**, **23**, and **24**. Therefore, as S_1 and S_3 go positive, gates **22** and **24** are unblocked to set latches **25** and **27** (normally reset). The outputs of these latches are up and at time T_2 gates **28** and **30** are unblocked to set latches **19** and **21**. The outputs of latches **19** and **21** go up to provide positive voltages to control lines C_1 and C_3 . Latch **20** remains reset so that the control line C_2 is still at a low potential at the time of the T_2 pulse. During the entire read-out cycle which follows the search cycle, latch **19** is set, latch **20** is reset, and latch **21** is set.

Recalling that sense lines S_5 and S_6 swing positively, inverters **29** and **30** provide a down level to gates **32** and **33** which are thereby blocked. So latches **35** and **36** remain reset to block gates **38** and **39**. However, sense line S_4 is down and inverter **28** provides a high level to gate **31** which is unblocked by the T_1 pulse to set latch

34. Latch **34** remains set throughout read-out and conditions gate **37**. Gate **37** passes to line **40** the condition of sense line S_4 . The output of OR gate **43** is then indicative of the state of the sense line S_4 which in turn is indicative of the data digits of the word in column Y_2 since columns Y_1 and Y_3 , which are also connected to S_4 , are blocked by the presence of a high positive potential on lines C_1 and C_3 from latches **19** and **21**. It can now be seen that regardless of subsequent changes to sense lines S_5 and S_6 , input lines **41** and **42** to OR gate **43** will remain negative. This is because latches **35** and **36** remain reset. Therefore, gates **38** and **39** remain blocked. However, latch **34** has been set to condition gate **37** during read-out.

The search portion of the cycle during which the desired word having the correct identification tag has been found is now completed and the read-out circuitry for the flow of data digits has been established. Now read-out commences.

Referring now to FIGURE 3, we see that after search, the condition of leads **18** are plus for Y_1 , open for Y_2 , and plus for Y_3 . During read-out each X strip is interrogated sequentially with an A.C. signal from generator **50**. At step 1, the zero area of the first digit position of the word is investigated by applying the A.C. signal to strip Y_7 . Then Y_8 , Y_9 , and Y_{10} are similarly interrogated. The results are shown in box **51**.

It can be seen that with latches **19** and **21** set and latch **20** reset and control lines C_1 and C_3 plus and C_2 minus, only those diodes having cathodes connected to control line C_1 can possibly change their states of conduction as a function of the condition of their associated Y strip. These diodes are D_3 and D_4 associated with point P_6 , and diodes D_{15} and D_{16} associated with point P_8 . Any change in diodes D_9 or D_{10} would result in a change in sense line S_5 or sense line S_6 , both of which cannot affect read-out since control line C_2 is negative during read-out regardless of the condition of sense line S_2 and line **41** is negative during read-out regardless of the condition of sense line S_5 . Only the changes of sense line S_4 affect the read-out and S_4 is connected to diodes D_1 , D_3 , and D_5 . Only diode D_3 changes its state of conduction as a function of the digits in the X_2 column. Therefore, the output of OR gate **43** is strictly a function of the data digits resulting from the interrogation of the column Y_2 word.

Previously reference has been made to a no-hole embodiment. By this is meant that the record card may contain the digits in the form of no holes rather than holes. A no-hole at a particular intersection point would indicate the character of the digit.

It is evident that similarity between the word lines Y and the similarity between the digit lines X allow any of the digit line combinations to be used as a tag. For example, memory could search for the word 01XX01 which is previously described, or 0XX01 which is the first column or 0X1X1 which is the second column where the X's represent the data digits. The user is also able to change the tag position at will before each memory search.

What has been described are various embodiments of the present invention. Other embodiments obvious to those skilled in the art from the teachings herein are contemplated to be within the spirit and scope of the following claims.

What is claimed is:

1. An associative memory system comprising storage means for storing words in the form of tag digits identifying each word and data digits associated with each word, individual read-out circuits associated with each of said words, first latching means for inhibiting some of said read-out circuits while enabling the remainder thereof, means to compare argument tag digits introduced to said storage means with the tag digits of each of said stored words in said storage means, means responsive to a match between said argument tag digits and the tag digits of one of said stored words for causing said first latching

means to inhibit said some of said individual read-out circuits, a second latching means, said responsive means causing said second latching means to inhibit the remainder of said individual read-out circuits except for said individual read-out circuit associated with said one word whereby a read-out path for the data digits associated with said one word is established through said individual read-out circuit associated therewith.

2. An associative memory system comprising storage means for storing words in the form of tag digits identifying each word and data digits associated with each word, individual read-out circuits associated with each of said words, means to compare argument tag digits introduced to said storage means with the tag digits of each of said stored words and to produce for each word a match signal indicative of a match between said argument tag digits and the tag digits of one of said words and no-match signals for the remainder of said words, means to feed said signals to their associated individual read-out circuits, means responsive to a match signal to establish a read-out path for the data digits of said one word through said read-out circuit associated therewith and means responsive to said no-match signals to inhibit the remainder of said read-out circuits.

3. An associative memory system as claimed in claim 2 in which each read-out circuit includes first and second control points, a first latching circuit controlling said first control point and a second latching circuit controlling said second point, means to feed said signals to both of

30

said first and second control points of said individual read-out circuit associated with said one word.

4. An associative memory system as claimed in claim 3 further including means to read-out said data digits of said one word through said established read-out path.

5. An associative memory comprising a record member divided into rows and columns and having holes therein representing word digits stored therein, digit and word electrodes on opposite sides of said member and respectively associated with said rows and columns, each of said words being composed of identifying tag digits and data digits, said holes forming electrical connection between coordinate digit and word electrodes, individual read-out circuits associated with each of said words, means for comparing argument tag digits introduced to said digit electrodes with the tag digits of each of said words and means responsive to a match between said argument tag digits and the tag digits of one of said words to establish a read-out path through the individual read-out circuit associated with said one word.
